(57) **CLAIM**

I claim the ornamental design for a handgun storage hanger, substantially as shown and described.

DESCRIPTION

FIG. 1 is a front perspective view of a handgun storage hanger showing my new design.

FIG. 2 is a top plan view thereof.

FIG. 3 is a bottom plan view thereof.

FIG. 4 is a front elevation view thereof.

FIG. 5 is a rear elevation view thereof.

FIG. 6 is a left side elevation view thereof; and,

FIG. 7 is a right side elevation view thereof.
